First Notification of Rectification received from the China National Intellectual Property Administration for Application No. 201830341661. X, dated Mar. 20, 2019, 2 pages.

Primary Examiner — Melanie H Tung(74) *Attorney, Agent, or Firm* — McDonnell Boehnen Hulbert & Berghoff LLP**CLAIM**

The ornamental design for a display screen or portion thereof with a graphical user interface, as shown and described.

DESCRIPTION

The FIGURE is a front view of a display screen or portion thereof with a graphical user interface.

The outermost broken lines illustrate a display screen or portion thereof and form no part of the claimed design. The remaining broken lines, illustrating portions of the graphical user interface, form no part of the claimed design.
